HAROLD A. WHEELER, OF GREAT NECK, NEW YORK, ASSIGNOR TO HAZELTINE CORPORATION, A CORPORATION OF DELAWARE

PUSH-PULL AMPLIFIER

Application filed August 17, 1929, Serial No. 386,543, and in Great Britain July 8, 1930.

This invention relates to improvements in amplifiers of the low frequency type adapted principally for amplifying currents in the audio frequency range. More particularly, 5 the invention is directed to improvements in thermionic amplifiers operating in so-called "push-pull" circuits.

An object of the invention is to provide an amplifier of the type mentioned which will 10 furnish substantially distortionless amplification without the necessity for utilizing a biasing battery or an initial negative biasing potential on the control circuits, or grids, of the thermionic tubes.

15 A further object is to provide an amplifier of the type specified adapted to furnish a high degree of substantially distortionless amplification.

20 A further object is to provide an amplifier of the type specified capable of delivering relatively large amounts of distortionless power output.

25 A further object is to provide an amplifier of the type specified wherein the signaling current delivered to the output circuit is caused to flow in series thru the plate circuits of the tubes oppositely connected thereto, such arrangement permitting the most efficient delivery of distortionless power to the 30 output circuit.

A further object is to provide a meter in the amplifier circuit which gives a continuous indication of the signal intensity.

35 A further object is to provide an amplifier of the type specified having a relatively low output impedance, as a consequence of utilizing no biasing potential on the grids of the tubes and further as a result thereof requiring a correspondingly lower anode supply 40 voltage than would otherwise be required where such biasing potential is used.

45 As a general proposition, one of the essential requisites to the distortionless amplification of the signaling currents by means of thermionic amplifiers consists in applying to the grids of the thermionic tubes a sufficiently large initial or permanent negative biasing potential to maintain them at all times negative relative to the corresponding cathodes 50 or filaments. For, if the incoming signal

wave has a sufficiently great peak value to carry the grid positive during a portion of each cycle, space current will flow in the grid circuit during such portion thereby causing an increased voltage drop in the input circuit associated with the tube with resultant decrease in voltage impressed between the grid and filament thereof as compared to that of the corresponding negative portion of the signaling wave. As a consequence of this, 55 60 the amplified signaling wave will contain a flattened portion during each interval that the grid is positive, which effect, of course, is distortion.

It is possible by means of a well designed 65 thermionic amplifier utilizing a sufficiently large permanent negative biasing potential on the grid, to obtain substantially distortionless amplification, but such a result is attained only by sacrificing certain other desirable features. In the first place, the use 70 of the negative biasing potential on the grid of a tube increases the plate circuit impedance thereof by a corresponding amount since the presence of the negative potential on the grid 75 impedes the flow of electrons from the filament to the plate, thus requiring a higher plate circuit voltage for a given plate current. The increased plate voltage required, together with the added grid bias voltage, involves an added expense to the amplifier 80 construction.

In order to partially overcome the above 85 enumerated disadvantages accompanying the use of a permanent negative biasing potential on the grids of the tubes, the so-called "push-pull" amplifier circuit was developed. The push-pull amplifier, as frequently constructed, comprises in essence an input transformer having the secondary 90 winding thereof connected between the respective grids of a pair of similar thermionic tubes, an output transformer having the primary winding thereof connected respectively between the anodes of said tubes, and having the cathodes connected in common to the midpoint of the input transformer secondary winding and also thru a direct plate current supply source to the midpoint of the output 95 transformer primary winding. 100

If now a sine wave of signaling current is impressed upon the input transformer of such a push-pull amplifier, there will at each instant of time be a signal voltage impressed 5 in a positive sense between grid and filament of one tube and an equal signal voltage impressed in the negative sense between grid and filament of the other tube, and since the voltages thus impressed produce additive effects 10 in the output transformer secondary, it is thus insured that each positive half cycle of amplified signaling current will be identical in wave form with the corresponding negative half cycle. This, however, does not necessarily mean that the amplified wave 15 will be distortionless; it merely means that the even harmonics of the fundamental frequency will be eliminated. The odd harmonics may still be present in sufficient magnitude to cause appreciable distortion.

In addition to the distortion effects noted 20 with the push-pull amplifier as commonly constructed, any grid current in flowing thru the input transformer secondary winding will cause a considerable voltage drop therein which will reduce the net signaling voltage applied between the grid and filament of the tubes and in this way limit the amplification obtainable.

It is proposed in the present invention to 30 improve the push-pull amplifier as commonly constructed in such manner as to substantially eliminate the above noted objectionable effects which result from operating the same without applying an initial or permanent negative biasing potential to the grids of the vacuum tubes. The improvement is 35 accomplished by serially interposing a high impedance element transversable by uni-directional current such as a choke coil but preferably a resistance in the lead connecting the midpoint of the input transformer secondary winding to the cathodes of the tubes. The objects to be accomplished by such a 40 modification are to prevent the flow of large currents in the grid circuits of the tubes and also to prevent the applied signaling wave from impressing an appreciable positive potential upon the grids since these two factors 45 when present to any considerable extent are the cause of the above noted objectionable effects.

Since with the above modification, current 50 flowing in the grid of either tube must traverse the high impedance element in returning to the cathode, such impedance operates automatically to limit the magnitude of the current flow. By utilizing an impedance element of sufficiently large magnitude, the 55 grid current can be limited to such a degree as to produce negligible distortion or amplification limiting effects due to the flow of grid current in the input transformer. Thus the grid current flowing in the input transformer secondary winding during signal re-

ception can be so limited that substantially no load will be placed on the transformer to limit the signal voltage applied to the grid of the negatively biased tube, or to introduce distortion effects into the system.

By making the above mentioned high impedance element of large magnitude relative to the operating filament-to-grid resistances of the tubes, substantially all of the voltage drop due to the flow of grid current will be across the high impedance element and very little across the tube input. This means that each tube will be substantially inactive while the grid thereof is maintained positive by the impressed signaling wave, but will strongly repeat the signal while the grid is maintained negative thereby, since in the latter case the grid is maintained negative thereby, since in the latter case the grid to filament impedance amounts to practically an open circuit across 85 which the full signaling voltage is necessarily impressed. Due to the opposite manner in which the tube input circuits are connected across their respective portions of the input transformer secondary winding, the grid of one tube will be charged positively by the applied signaling wave at each instant that the grid of the other tube is charged negatively thereby, with the result that one tube will repeat positive portions and the other tube negative portions of the signaling wave to the output circuit. Further the negatively charged tube will be responsible for substantially the entire signal wave repeated at each instant to the output circuit, with the positively charged tube contributing very little. This mode of operation is in marked contrast to that of the push-pull circuit amplifier as commonly constructed in which case it is the positively charged tube which is principally 95 active in repeating the signal.

A further important advantage resulting 100 from the interposition of the high impedance element in the lead connecting the cathodes in common to the midpoint of the input transformer secondary winding is that such an arrangement automatically operates to impress at each instant across the tube having its grid negative, substantially all of the voltage induced in both portions of the transformer secondary winding. In other words, the operation is just as though the entire secondary winding were at each instant connected across the input of the tube the grid of which is maintained negative by the signaling current. Due to this fact the incoming signaling wave is impressed to the greatest extent across the tube which is active in repeating the signal thereby offering a maximum degree of 115 amplification.

The manner in which the above effect is brought about is as follows. The flow of grid current due to the voltage induced in the portion of the transformer connected to the tube having its grid positive, causes a 120

voltage drop in the high impedance element which makes the terminal thereof connected to the midpoint of the transformer secondary, negative with respect to the terminal 5 connected to the cathodes. This negative potential is applied through the transformer winding to the negative grid of the opposite tube and thus adds to the negative voltage applied thereto due to the induced signaling 10 voltage in the portion of the secondary winding connected to the tube having its grid negative. And since as was stated, practically the entire voltage drop due to the voltage induced in the transformer secondary connected 15 to the tube having its grid positive is across the high impedance element, it follows that the total voltage applied to the tube having its grid negative amounts to substantially the voltage induced in the entire secondary 20 winding.

Due to the fact that with the proposed arrangement of the push-pull amplifier as disclosed herein only one tube at a time is active in delivering energy to the output circuit, it has been found that the ordinary 25 means for connecting the tubes to such output circuit, namely, through an output transformer having the primary winding tapped at the midpoint and connected directly 30 through a space current supply source to the filaments, does not permit the maximum delivery of power to the output circuit. Since only one tube at a time is "active", the output transformer in such case acts as a three- 35 winding transformer having a single primary connected to the plate resistance of the active tube and a pair of windings connected respectively to the plate resistance of the inactive tube and to the output circuit. The 40 dynamic plate resistances of both tubes are thus connected effectively in parallel with the output circuit so that the plate resistance of the inactive tube acts as a dissipative shunt across the output circuit.

45 It is well known that in the operation of thermionic tubes the maximum output consistent with good operation is obtained when the load impedance is substantially greater than the generator impedance. In the present instance, since the active tube is the generator, while the inactive tube and the output circuit connected in parallel constitute the effective load impedance, it will be seen that with the commonly used push-pull arrangement, the load impedance is always less than 50 that of the generator.

In contrast with the above arrangement, wherein the output circuit and the plate resistances of the tubes are effectively in parallel, it is possible to so arrange the elements 55 that the amplified signal current flows in series through the active and inactive plate resistances and through the output circuit. With such an arrangement, it is evident that 60 the load impedance will always be greater

than the generator impedance so that the above ideal condition can be realized wherein substantially the entire output from the active tube is delivered to the output circuit. For a given amount of power delivered to the 70 output circuit, the proposed series arrangement introduces considerably less distortion due to the non-linear plate current characteristic of the tubes than does the parallel arrangement, since in the former case considerably less signaling current flows in the plate circuit of the active tube. 75

The series arrangement for the output circuit is obtained by interposing a high impedance element traversable by unidirectional current in the lead connecting the midpoint of the output transformer primary winding through the space supply source to the cathodes of the tubes in common. A 80 resistance element may be used for this purpose, but preferably a choke coil should be used since it has a considerably smaller effect on the total resistance of the space supply circuit. With such an arrangement, only the steady direct plate current supply flows 85 through the high impedance element. Substantially all of the amplified signaling current is forced to flow in series through the active and inactive tubes and through the 90 output circuit. 95

The series type of output circuit is inferior to the usual output transformer arrangement when applied to the push-pull amplifier as commonly constructed and utilizing a high initial negative-grid bias for 100 the tubes. The reason is that for such an amplifier both tubes are about equally active at each instant in delivering current to the output circuit, and the less active tube is 105 the one with the higher instantaneous plate resistance.

Referring now to the drawings—

Fig. 1 shows in circuit diagram form a 110 push-pull amplifier having its input circuit arranged in accordance with the present invention but with the output circuit in accordance with the ordinary type of amplifier.

Fig. 2 shows in circuit diagram form a 115 push-pull amplifier having both the input and output circuits arranged in accordance with the present invention, wherein the novel results are obtained by the use of high resistance elements.

Fig. 3 shows a modification of Fig. 2 wherein choke coils instead of resistances are used 120 for obtaining the novel results.

Fig. 4 shows a two-stage amplifier in 125 accordance with the present invention utilizing both resistance and inductive elements to obtain the operative features of the present invention.

Fig. 5 shows an amplifier in accordance 130 with the present invention wherein a special type of loud speaker unit is connected direct-

ly in the anode circuit of the tubes with resultant advantages as pointed out below.

- The expression "divided input section" and "divided output section" as used in the specification and claims denotes the push-pull connection of the amplifier tubes in which the cathodes of the push-pull connected tubes are joined together and connected respectively to an intermediate point of the input circuit and 5 output circuit, while the grids are connected to respective opposite outer terminals of the input circuit and the anodes are connected to opposite outer terminals of the output circuit.
- 10 Referring to Fig. 1, the amplifier comprises vacuum tubes V_1 and V_2 each having grid G , plate or anode P , and filament or cathode F . The grids of tubes V_1 and V_2 are connected respectively to the upper and 15 lower terminals of the secondary winding S_1 of transformer T_1 , the primary P_1 of which is connected between a pair of input terminals I . An auto-transformer T_2 is connected between the cathodes of the respective 20 tubes, the transformer terminals being connected in addition to a pair of output terminals O . The cathodes in common are connected by means of lead 1 thru a milliammeter M , for indicating the energy level of 25 the impressed signal and through a high resistance R_1 to the midpoint of the input transformer secondary S_1 . In addition, the cathodes are connected by means of lead 2 through a space supply source B to the 30 midpoint of the output transformer T_2 . The auto-transformer T_2 may be replaced by a two winding transformer similar to T_1 , having the primary windings connected to the 35 output sections of the tubes and the secondary winding connected between the output terminals O . The cathodes F are heated by any suitable means, not shown.

In the operation of the amplifier assume 40 that at a given instant a signaling wave impressed upon the input terminals I is such as to make the lower terminal of the secondary winding S_1 negative relative to the upper terminal thereof. The voltage thus induced in the secondary winding S_1 will carry the 45 grid of tube V_2 negative and that of V_1 positive. The positive potential on the grid of tube V_1 will cause a current to flow in the space path from the filament F to grid G of the tube, through the upper portion of the 50 secondary winding S_1 and thence serially through the high resistance element R_1 and meter M back to the filament of the tube. The large magnitude of the resistance element R_1 will limit the flow of grid current 55 in the circuit traced to a negligibly small value as compared to the impressed signaling wave, and will thus prevent the placing of an appreciable load upon the transformer which otherwise would reduce the terminal voltage 60 of the secondary winding S_1 . Further-

more, the resistance R_1 being of relatively large magnitude compared to the filament to grid resistance of the tube, practically all of the voltage drop due to the flow of grid current in the circuit traced will be across the 65 resistance element R_1 and very little will be impressed in a positive sense between filament and grid of the tube V_1 with the resultant advantages pointed out above.

At the same time that the action described 70 above is taking place in the grid circuit of tube V_1 , the voltage induced in the lower portion of the secondary winding S_1 is impressed in a negative sense between grid and filament of tube V_2 . Since the grid-to-filament impedance of the tube amounts to practically an open circuit, the full terminal voltage of the lower portion of the secondary winding S_1 is impressed directly between grid and filament of tube V_2 , since for this 75 tube there is no flow of grid current through the resistance element R_1 to reduce the net voltage applied to the tube.

In addition to the negative potential applied to the grid of tube V_2 due to the voltage 80 induced in the lower portion of the transformer winding S_1 , an additional negative potential will be applied thereto due to the voltage drop across the resistance element 85 R_1 caused by the current flowing in the grid circuit of tube V_1 . This grid current flowing in the circuit traced above flows through the resistance element R_1 in such a direction as to render terminal 3 thereof connected to the winding S_1 , negative relative to terminal 4 90 thereof connected to the cathodes. Since terminal 4 is connected to the cathode of tube V_2 , as well as that of tube V_1 , the potential drop across resistance R_1 is immediately applied through the lower portion of transformer winding S_1 between the grid and filament of tube V_2 and thus increases the negative 95 potential applied to the grid of that tube by the amount of the potential drop in the resistance element R_1 . Further since, 100 as was explained above, practically the entire potential drop due to the voltage impressed in the upper portion of winding S_1 is across the resistance element R_1 , the total negative charge of the grid of tube V_2 due 105 to the potential drop across the resistance element R_1 and the voltage induced in the lower portion of the winding S_1 is practically 110 the same as the voltage induced in the entire secondary winding S_1 .

When the signaling voltage applied to the input terminals I is such as to render the upper terminal of winding S_1 negative relative to the lower terminal, the conditions described above will be reversed, and the grid of tube V_1 will be carried negative and that of tube V_2 positive. Current will thus flow from the space path from filament to grid of tube V_2 and in series through the lower portion of the winding S_1 , the resistance R_1 115

and the meter M back to the filament. The voltage drop across the resistance element R_1 due to this current flow will apply a negative potential to the grid of tube V_1 which 5 grid will be carried still further negative by the voltage induced in the upper portion of the winding S_1 . A large negative potential will thus be impressed upon the grid of tube V_1 while a relatively small positive potential 10 will be impressed upon the grid of tube V_2 .

As a result of the mode of operation described above, the tube having its grid negative at a given instant will strongly repeat the signal to the output circuit, while the tube 15 having its grid positive will have very little effect thereon. Due, however, to the manner of combining the amplified signaling current in the output transformer T_2 , the signaling waves simultaneously repeated by both 20 tubes will produce additive effects in the output circuit so that the signal weakly repeated by the tube having its grid positive will add its effect therein to that of the negative tube having its grid negative.

With the arrangement of Fig. 1, the plate 25 resistances of tubes V_1 and V_2 are connected effectively in parallel with an output circuit connected across terminal O, which results in a relatively large portion of the signaling 30 energy delivered by the active tube being dissipated in the plate resistance of the inactive tube.

Referring now to Fig. 2, if a high impedance element such as the resistance R_2 35 be interposed in lead 2 connecting the midpoint of the primary winding P_2 of the output transformer T_2 with the filaments F of the tube, the operation of the output circuit will be essentially changed in that the amplified 40 signaling current will flow in series through the plate resistances of both the active and inactive tubes.

While no signals are being received, a steady direct current flows through the resistance R_2 , which is the sum of the space currents supplied to the plate circuits of tubes V_1 and V_2 . If now a signaling voltage is impressed upon the input terminals I in such manner as to carry the grid of tube V_2 negative, there will be a corresponding decrease 50 in the plate current of this tube. As a result the current flowing through the resistance R_2 will decrease slightly, thus increasing the available potential between terminal 4 and the midpoint of winding P_2 , which added potential being immediately impressed across the plate circuit of tube V_1 will increase the plate current thereof by substantially the same amount that the plate current of tube 55 V_2 is decreased. Since, therefore, the plate current of tube V_1 simultaneously increases by substantially the same amount that that of tube V_2 decreases, substantially all of the amplified signaling current in effect flows in 60 series through the plate resistances of tubes 65

V_1 and V_2 and both portions of the primary winding P_2 , the resistance element R_2 being so great that practically no change in current takes place therein. Since the impedance of the primary winding P_2 is determined by the 70 impedance of the output circuit connected to terminals O, it will thus be seen that the repeated signal in effect flows in series through the resistances of the active and inactive tubes and through the output circuit. 75

Fig. 3 shows an arrangement whereby high impedance choke coils L_1 and L_2 replace the resistance elements R_1 and R_2 , respectively, of Fig. 2. The use of the choke coil L_2 permits the use of a smaller battery B to supply a 80 given space current to the tubes than is the case with the arrangement of Fig. 2. The circuit of Fig. 3 operates on the signaling wave in the same manner as that of Fig. 2.

Fig. 4 shows the method of arranging a 85 two-stage amplifier in accordance with the present invention. The output sections of tubes V_1 and V_2 , comprising the first amplifier stage, are connected by means of transformer T_1 to the input sections of tubes V_3 and V_4 comprising the second amplifier stage. The output sections of tubes V_3 and V_4 in 90 turn are connected through transformer T_2 to the output terminals O.

In order to provide the series arrangement 95 for the output circuit of the first amplifier stage, the resistance R_2 is serially interposed in lead 2. The resistance R_1 is serially interposed in lead 1 associated with the input circuit to the second amplifier stage, while the choke coil L_2 is connected in lead 2 of the output circuit thereof in order to cause the amplifier to operate in accordance with the present invention. 100

The amplifier shown in Fig. 5 is similar 105 to that shown in Fig. 1, with the exception that the anode circuits of tubes V_1 and V_2 contain the voice frequency actuating coils 5 and 6 respectively of a special type of loud speaker, known as a "Farrand inductor dynamic" speaker. This speaker, which is especially adapted for use with the type of amplifier disclosed herein, comprises the cone shaped acoustical diaphragm 7, a permanent horse shoe magnet 8 having affixed to the respective poles thereof oppositely positioned U shaped pole pieces 9 and 10. The pole pieces 9 and 10 are so dimensioned and positioned as to leave equal air gaps between the opposed legs thereof, in which space an armature 11 is suspended in such manner as to be free to vibrate in a perpendicular direction. A rod 12 connects the lower end of armature 11 to the central point of the cone 7, whereby the cone is vibrated in accordance with vertical movements of the armature. 110 115 120

The coil 5 is placed about the upper leg of pole piece 10 and coil 6 about the lower leg of pole piece 9. Also coil 5 is connected directly in the plate circuit of tube V_1 , and 125 130

coil 6 directly in the plate circuit of tube V_2 in such manner that the flux set up by the direct space current in each case aids the flux of the permanent magnet 8, threading the air gaps between the pole pieces.

5 The armature 11 has a length about equal to the distance between the centers of the legs of the pole piece, and is so positioned symmetrically within the air gap as to be pulled 10 equally in opposite vertical directions by the steady flux threading the two air gaps respectively between the pole pieces.

If now a signal wave be impressed upon the input terminals of the amplifier, the action 15 of the amplifier is such that the current in signal coil 5 decreases when the grid of tube V_1 is negative, and at the same time the current in signal coil 6 remains constant at the normal direct current value, or increases very 20 little because the grid of tube V_2 is positive. Likewise, when the grid of the tube V_1 is positive the current in signal coil 5 is practically 25 at the normal direct current value and the current in signal coil 6 is decreased. From the foregoing, it is seen that the signal coils are alternately operative and furthermore 30 the coil which is inoperative exerts no influence upon the coil which is operative. This gives the result that the inactive tube of low plate resistance is not effectively a shunt 35 across the output of the active tube, as would be true if a single output transformer were utilized.

The principal advantage of connecting the 40 loud speaker directly in the output circuit is that all frequencies operate on the speaker unit to equal advantage, whereas, if the speaker were connected directly to the terminals of an output transformer, as for example, to terminals O of Fig. 2, the lower 45 frequencies would in general be discriminated against. Another advantage of the arrangement of Fig. 5 lies in the elimination of the output transformer T_2 , which of course, represents an economy in amplifier construction. The greatest distortionless power output 50 is secured when coils 5 and 6 are practically without mutual magnetic coupling and when the effective impedance of each coil is approximately three times the output impedance of the vacuum tubes individually connected thereto.

With the series arrangement for the output circuit as disclosed in Figs. 2, 3 and 4, it has 55 been found that best results are obtained when the apparent load impedance connected between the anodes of the tubes equals approximately four times the effective cathode to plate impedance of each tube.

60 I claim:

1. A low-frequency amplifier for providing a high degree of substantially distortionless amplification in the absence of a negative biasing potential in the control circuits of 65 said amplifier, comprising divided input and

divided output sections having connected in opposition therebetween a pair of vacuum tubes each including cathode and grid electrodes, and means interposed between said cathodes and said input section for rendering each tube substantially inactive while its grid is made positive by electric waves in said input section, whereby said waves are repeated by the tube having its grid negatively charged by said waves. 70 75

2. A low-frequency amplifier for providing a high degree of substantially distortionless amplification in the absence of a negative biasing potential in the control circuits of 80 said amplifier, comprising divided input and output sections having connected in opposition therebetween, a pair of vacuum tubes each including cathode and grid electrodes, and means interposed between said cathodes and said input section adapted to cause electric waves in said input section to be applied in substantial entirety upon the tube negatively charged thereby, whereby such tube 85 alone repeats the signal.

3. In an electric wave repeating apparatus 90 for providing a high degree of substantially distortionless amplification in the absence of biasing potentials in the control circuits of said apparatus, divided input and output sections having connected in opposition therebetween a pair of vacuum tubes each including cathode and grid electrodes, and a high resistance free from reactance interposed between said cathodes and said input section for substantially preventing the 100 flow of space current in the grid circuits of said tubes, whereby signal waves present in said input sections are impressed in substantial entirety upon the tube whose grid momentarily receives a negative potential therefrom so that said latter tube alone repeats the signal. 105

4. A low-frequency amplifier for providing a high degree of substantially distortionless amplification in the absence of a biasing 110 potential in the control circuits of said amplifier, comprising the combination of two repeating elements having a cathode, an anode and an input electrode, the cathodes of both said elements being connected together, an input repeating coil the secondary winding of which is connected at an intermediate point to said cathodes, and at its opposite terminals to said input electrodes respectively, 115 and a high resistance interposed between said cathodes and said secondary winding adapted of itself to substantially prevent the flow of current in the control circuits of said repeating elements, whereby signal waves present 120 in said repeating coil are impressed in substantial entirety upon the element whose input electrode momentarily receives a negative potential therefrom, so that said latter 125 element alone repeats the signal. 130

5. A push-pull amplifier for providing a high degree of substantially distortionless amplification in the absence of biasing potential in the grid circuits of said amplifier, comprising divided input and divided output circuits having connected in opposition therebetween, a pair of vacuum tubes each including cathode, anode and grid electrodes, a high impedance interposed between said cathodes and said input circuit for substantially preventing the flow of current in the grid circuits of said tubes, whereby signal waves present in said input circuit are impressed in substantial entirety upon the tube whose grid momentarily receives a negative potential therefrom so that said latter tube alone repeats the signal, and a resistance free from reactance interposed between said cathodes and said output circuit for causing electric waves repeated in said output circuit to flow in series through the anode circuits of both said tubes and said output circuit.
6. A low-frequency amplifier for providing a high degree of substantially distortionless amplification in the absence of negative biasing potential in the control circuits of said amplifier, comprising divided input and divided output circuits having connected in opposition therebetween, a pair of vacuum tubes each including cathode, anode and grid electrodes, a high resistance interposed between said cathodes and said input circuit adapted of itself to substantially prevent the flow of current in the grid circuits of said tubes, whereby signal waves present in said input circuit are impressed in substantial entirety upon the tube whose grid momentarily receives a negative potential therefrom so that said latter tube alone repeats the signal, and an inductive reactance interposed between said cathodes and said output circuit for causing electric waves repeated in said output circuit to flow in series through the anode circuits of both said tubes and said output circuit.
7. A low-frequency amplifier for providing a high degree of substantially distortionless amplification in the absence of negative biasing potential in the input circuits of said amplifier, comprising the combination of two repeating elements each having a cathode, an anode and an input electrode, said cathodes being connected together, an input repeating coil and an output repeating coil, the secondary winding of said input repeating coil being divided and the divisions thereof connected to said input electrodes respectively, and the primary winding of said output repeating coil being divided and the divisions being connected to said repeating elements respectively, a high resistance free from reactance interposed between said cathodes and an intermediate point of said input repeating coil for substantially preventing the flow of current in the control circuits of said repeating elements, whereby signal waves present

in said input coil are impressed in substantial entirety upon the repeating element whose input electrode momentarily receives a negative potential therefrom so that said latter element alone is effective to repeat the signal, and an inductive reactance interposed between said cathodes and an intermediate point of said output repeating coil for causing electric waves repeated in said output circuit to flow in series through the output resistances of both said repeating elements.

8. An electric wave repeating apparatus comprising in combination a pair of electron discharge devices each including anode, cathode and grid, an input transformer having a winding connected between said grids respectively, a connection from an intermediate point of said winding to said cathodes in common through impedance means adapted to cause a signaling wave impressed upon said input transformer to be repeated at each instant in substantial entirety by the said device which receives a negative potential therefrom.

9. An electric wave repeating apparatus comprising a pair of electron discharge devices each having anode, cathode and grid, an input transformer having a secondary winding connected between said grids respectively, a connection from an intermediate point of said winding connected to said cathodes in common through impedance means of large magnitude relative to the lowest grid-to-cathode resistances of said devices during operation for causing an impressed signaling wave to be repeated at each instance in substantial entirety by the said device which receives a negative potential therefrom.

10. An electric wave repeating apparatus comprising in combination a pair of electron discharge devices each having anode, cathode and grid, an input transformer having a winding connected between said grids respectively, a connection from an intermediate point of said winding to said cathodes in common, through impedance means adapted to cause a signaling wave impressed upon said transformer to be repeated at each instant in substantial entirety by the said device which receives a negative potential therefrom, an output transformer having a winding connected between said anodes respectively, and a connection from an intermediate point of said winding to said cathodes in common through impedance means traversable by direct current, adapted to cause the repeated signaling wave to flow in series through the anode circuits of both said devices.

11. An electric wave repeating apparatus comprising in combination a pair of electron discharge devices each including anode, cathode and grid, an input transformer having a secondary winding connected between said grids respectively, a connection from an intermediate point of said secondary winding

to said cathodes in common through a resistance of large magnitude relative to the lowest grid-to-cathode resistances of said devices during operation whereby a signaling wave impressed upon said input transformer is repeated at each instant in substantial entirety by the said device which receives a negative potential therefrom, an output transformer having a primary winding connected between said anodes respectively, a connection from an intermediate point of said primary winding to said cathodes in common through a space current supply source and an inductance of sufficient magnitude to cause the repeated signaling wave to flow in series through the anode circuits of both said devices and said primary winding.

12. The combination with a thermionic amplifier comprising a pair of vacuum tubes each having anode, cathode and grid, and a divided input circuit connected at an intermediate point to said cathodes in common through a high impedance and at opposite outer terminals to said grids respectively, whereby signal waves present in said input circuit are impressed in substantial entirety upon the tube whose grid momentarily receives a negative potential therefrom so that said latter tube alone repeats the signal, of a loud speaker unit including means for producing a permanent magnetic flux adapted to maintain in dynamic equilibrium an armature affixed to an acoustical unit, a pair of signal current coils for actuating said armature situated respectively at opposite ends thereof, and means so connecting said coils in the anode circuits of said tubes respectively that signal waves received at the input of said amplifier tubes affect said coils alternately and produce distortionless resultant effects upon said armature.

In testimony whereof I affix my signature.
HAROLD A. WHEELER.

DISCLAIMER

1,878,741.—*Harold A. Wheeler*, Great Neck, N.Y. PUSH-PULL AMPLIFIER. Patent dated September 20, 1932. Disclaimer filed October 20, 1933, by the patentee, assignee, *Hazeltine Corporation*, consenting.

Therefore enters this disclaimer to claims 1, 2, 3, 4, 8, and 9 of said Letters Patent, which are in the following words, to wit:

“1. A low-frequency amplifier for providing a high degree of substantially distortionless amplification in the absence of a negative biasing potential in the control circuits of said amplifier, comprising divided input and divided output sections having connected in opposition therebetween a pair of vacuum tubes each including cathode and grid electrodes, and means interposed between said cathodes and said input section for rendering each tube substantially inactive while its grid is made positive by electric waves in said input section, whereby said waves are repeated by the tube having its grid negatively charged by said waves.

“2. A low-frequency amplifier for providing a high degree of substantially distortionless amplification in the absence of a negative biasing potential in the control circuits of said amplifier, comprising divided input and output sections having connected in opposition therebetween, a pair of vacuum tubes each including cathode and grid electrodes, and means interposed between said cathodes and said input section adapted to cause electric waves in said input section to be applied in substantial entirety upon the tube negatively charged thereby, whereby such tube alone repeats the signal.

“3. In an electric wave repeating apparatus for providing a high degree of substantially distortionless amplification in the absence of biasing potentials in the control circuits of said apparatus, divided input and output sections having connected in opposition therebetween a pair of vacuum tubes each including cathode and grid electrodes, and a high resistance free from reactance interposed between said cathodes and said input section for substantially preventing the flow of space current in the grid circuits of said tubes, whereby signal waves present in said input sections are impressed in substantial entirety upon the tube whose grid momentarily receives a negative potential therefrom so that said latter tube alone repeats the signal.

“4. A low-frequency amplifier for providing a high degree of substantially distortionless amplification in the absence of a biasing potential in the control circuits of said amplifier, comprising the combination of two repeating elements having a cathode, an anode and an input electrode, the cathodes of both said elements being connected together, an input repeating coil the secondary winding of which is connected at an intermediate point to said cathodes, and at its opposite terminals to said input electrodes respectively, and a high resistance interposed between said cathodes and said secondary winding adapted of itself to substantially prevent the flow of current in the control circuits of said repeating elements, whereby signal waves present in said repeating coil are impressed in substantial entirety upon the element whose input electrode momentarily receives a negative potential therefrom, so that said latter element alone repeats the signal.”

“8. An electric wave repeating apparatus comprising in combination a pair of electron discharge devices each including anode, cathode and grid, an input transformer having a winding connected between said grids respectively, a connection from an intermediate point of said winding to said cathodes in common through impedance means adapted to cause a signaling wave impressed upon said input transformer to be repeated at each instant in substantial entirety by the said device which receives a negative potential therefrom.

“9. An electric wave repeating apparatus comprising a pair of electron discharge devices each having anode, cathode and grid, an input transformer having a secondary winding connected between said grids respectively, a connection from an intermediate point of said winding connected to said cathodes in common through impedance means of large magnitude relative to the lowest grid-to-cathode resistances of said devices during operation for causing an impressed signaling wave to be repeated at each instance in substantial entirety by the said device which receives a negative potential therefrom.”
